UNITED STATES PATENT OFFICE.

EDGAR G. RICHARDS, OF MADISON, WISCONSIN, ASSIGNOR TO THE NORTHERN ELECTRICAL MANUFACTURING COMPANY, OF SAME PLACE.

DESIGN FOR A MOTOR-FRAME.

SPECIFICATION forming part of Design No. 27,480, dated August 3, 1897.

Application filed June 30, 1897. Serial No. 643,039. Term of patent 14 years.

To all whom it may concern:

Be it known that I, EDGAR G. RICHARDS, a citizen of the United States, residing at Madison, Dane county, Wisconsin, have invented 5 a certain new and useful Design for a Frame for Motors, of which the following is a description.

My design relates to frames for motors, and is illustrated in the accompanying drawings, 10 wherein—

Figure 1 is a perspective view of a motor-frame embodying my design. Fig. 2 is a plan view of the same.

As illustrated in the drawings, the frame 15 consists of the central part A, provided with the removable end pieces B. These end pieces are fastened to the central piece and are pro-

vided with the bearings C for the shaft of the motor. The end pieces are each provided with the projecting part D, each of which are 20 provided with bearings and are in alinement, so that any suitable shaft may be mounted in such bearings.

The essential feature of my design is the central piece A, provided with the end pieces 25 B, each having the two bearings C and D.

I claim—

The design for a motor-frame as herein shown and described.

EDGAR G. RICHARDS.
